UNITED STATES PATENT OFFICE.

DAVID GEORGE, OF LYNDAL, WESTCROSS, WALES.

PACKING OF GOODS.

Application filed August 26, 1926, Serial No. 131,756, and in Great Britain April 16, 1925.

This invention relates to the packing of goods of a nature that will deteriorate under the influence of moisture and also to relatively heavy goods that may become damaged by the breakage of the packing owing to rough handling in transit.

More particularly the invention relates to the packing of goods, such as blackplates, terneplates, tinplates and other metal sheets, and the object of the invention is to provide improved packing means of the type comprising an inner waterproof casing adapted to be hermetically sealed and an outer protective covering or casing.

15 The invention consists in packing means of the type described comprising an inner hermetically sealed casing and a protective outer casing and is characterized by the feature that the inner casing, formed of tinplate, terneplate, blackplate, galvanized iron sheet or the like comprises an open-ended tube, the parts adjacent such ends being adapted to form the end walls of the casing by being folded flat in overlapping relation 25 and soldered in such position.

A packing for tinplates has been proposed comprising an inner ordinary tin case, soldered airtight, and an outer steel case comprising a body or box part reinforced by an 30 inner wooden skeleton or inner frame, and a lid or cover having flanges which are double seamed to flanges on the body.

The outer protective case according to the invention may also be formed of sheet metal 35 plates combined with inner wooden slats to which such plates are nailed or otherwise secured.

Further features of invention will be hereinafter described.

40 The accompanying drawings illustrate packings and tools and machines that may be used therewith according to the invention;—

Figure 1 is a perspective view showing a 45 tubular inner casing;

Figure 2 is a corresponding view showing one end folded;

Figures 3 and 4 illustrate a bending device in use;

50 Figures 5, 6 and 7 are side, end and plan views of a machine for use in loading and folding the end of an inner casing;

Figure 8 is a perspective view of an outer casing according to one form;

55 Figure 9 shows a sectional plan;

Figure 10 shows a part section of a modified form of outer casing;

Figures 11 and 12 illustrate details of the end of the outer casing;

Figure 12^a shows in perspective a modified 60 form of end casing member;

Figures 13 to 16 show details of buffers for protecting the corners of the plates.

In carrying the invention into effect as applied, for example, to the packing of bundles 65 of tinplates comprising 112 plates, 20 inches by 14 inches, weighing 108 lbs. and having a combined thickness of 1 3/4 inches, the inner casing is formed in the following manner:—

A sheet of tinplate, terneplate, blackplate, galvanized or other sheet metal 20 is provided of suitable thickness, say 30 gauge, B. w. g. The sheet is of such length as to permit its extending around the bundle with the ends overlapping. The overlapping ends 70 are adapted to be hooked or rolled together and the seam 21 so formed is soldered or otherwise hermetically sealed. A suitable length of sheet for this purpose would be 32 1/2 inches. The width of the sheet is such that it will extend about 1 3/4 inches beyond the bundles and is thus about 23 1/2 inches wide.

When the sheet is formed into tubular shape as shown in Figure 1 the seam 21 is 85 adapted to lie along one side.

The open ends 22, 23 of the tube are adapted to be folded in a manner similar to the folding of a paper parcel.

Conveniently the side portions 24 at one 90 end are first folded in by any suitable appliance or bent over by hammering and then the top and bottom parts 25 are folded or beaten over to overlap (see Figure 2), a suitable former being inserted for this purpose 95 if desired. The seams are then soldered to form watertight joints. The folding in of the side portions may be effected as shown in Figures 3 and 4 by means of tongs having the handles 26 arranged at an angle to the jaws 27 whereby the latter may be turned through a right angle without the handles fouling the end of the box. The width and length of the jaws 27 are made to suit the width of the box and the amount of overlap 100 or bend.

After filling the casing with the plates, the open end is similarly folded over and soldered. When filled, a slight clearance is left, say about 1/8 inch.

The tubular inner casing may be formed in any suitable known way.

- In order to facilitate the handling of the case when filled and preparatory to closing the open end, a pivoting flap or table 46 (Figures 5, 6 and 7) may be provided associated with a bench 47. The table is provided with an adjustable fence 48 to form a shelf or rest adapted to support the casing.
20. The fence is adjusted to a position so that the casing will project above the upper edge of the table a distance equal to or slightly more than the overlap of its open end. The casing is mounted upon the table (which is inclined at a suitable angle) and the bundle of plates slid into the casing. The table is then pivoted towards the bench and when the centre of gravity passes the pivotal axis 49 the tendency of the table will be to rotate towards the bench so that the table will come to rest in a position in which the casing 20 will be gripped at its upper end between the edge of the bench and the table. The open end of the casing is then folded in and sealed. The pivoting of the table may be controlled by any suitable gear, such as a sector and pinion, a worm and worm wheel, levers or other known device. The table may also be counterweighted, if desired, and locking means may be provided for locking the table in any desired position. For instance, a notched sector may be provided and a lever carrying a locking pawl may be attached to the pivoting axle.
25. The dimensions of the table or flap 46 are of some importance as will be hereinafter referred to and for a bundle of plates of the dimensions set out above the width of the table may be 29 inches, the depth being sufficient to take the longest plate to be dealt with. The casing is placed to one side of the table. The table may be formed of any suitable material, metal or wooden, with a metal surface.
30. Referring to Figures 13 to 16, in order to protect the corners of the plates 51 which may become damaged by the casing being dropped on a corner, buffers 50 may be inserted into the casing before the plates are loaded therein. The buffers may comprise strips of tinplate 52 of suitable gauge and width, say $1\frac{1}{2}$ inches, and of such length as to extend the length of the case plus the length of the doubled-up ends, said ends being folded two, three or any other suitable number of times, as shown respectively in Figures 14, 15 and 16. These strips are inserted into the casing before loading and when loading is effected the upper ends of the strips are folded to form buffers for the upper corners.
35. Referring now to the outer protective casing, as shown in Figures 8 to 12, this may be formed of a pair of plates 53 of suitable size and gauge. These plates are bent up to

form channel members and the flanges are nailed to inner strips of wood 54 so as to form a tubular casing of internal dimension suitable to accommodate the inner casing. The plates 53 extend beyond the ends of the 70 wooden strips 54 a distance equal to the thickness of the strip. It will be obvious that a single plate suitably bent may be used instead of two plates.

It is desirable with either form to arrange 75 that the seams or joins shall be disposed along the side or sides of the box. The edges of the sheet or sheets that form the ends of the outer case may be beaded or bent over and planished so as to provide a smooth edge 80 whereby cutting of the hands of the operator during the packing operation is prevented. The dimensions of the plate will obviously be increased to allow for these turned-over edges.

85. The ends of the outer case are formed of wooden strips 55 which are covered with sheet metal 56 in channel form and nailed to the strips. When in position within the ends of the main body nails may be driven 90 through the main body and into the end strips, thus passing through two or three thicknesses of metal before insertion into the wood according to the amount of turnover provided at the edges of the sheet referred to.

95. The sheet metal plates associated with the end strips of wood may be formed by cutting out corner pieces by longitudinally extending cuts and then outwardly extending cuts (see Figure 12). By such arrangement the plates are provided with side and end flanges and the latter may be of such length that they may be engaged by nails driven into the side strips. The number of 100 nails used and the positions thereof may obviously be varied.

105. According to another form as shown in Figure 12^a, the end wooden slats 55 may be covered by a strip of sheet metal 62 the 110 ends 63 of which are simply bent tightly over the ends of the slat, no nailing in this case being necessary.

115. The partly uncovered face 62 of the slat faces inwardly when in position.

Reverting now to the sealed inner case which was sealed and mounted upon the table or flap 46, the table is pivoted backwardly into a position slightly out of the vertical and the outer case, with one end 120 closed in, put over the inner case and forced down over it until the outer case reaches the shelf 48 supporting the inner case.

In order to facilitate this operation the angle of the shelf 48 with the table 46 may 125 be slightly more than a right angle so that the case when resting upon the shelf will be slightly separated from the table.

The table is then pivoted to a substantially horizontal position and the partly 130

completed package turned through 90° so that the closed end overhangs the end of the table (as shown in dot-and-dash lines, Figure 7).

5 The package may then be lifted and transferred to the bench, if necessary upended and jerked to cause the inner case to fall to the closed end of the outer case and the open end of the latter then closed by 10 the end piece and nailed up.

If thought desirable, the package may now be further secured by wire binders in known manner, the wooden strips permitting a denting of the outer case at the edge 15 to prevent slipping of the wires. If necessary the outer case may be provided with projections or ridges to prevent slipping when the bundles are stacked in piles.

Having now described my invention, 20 what I claim as new and desire to secure by Letters Patent is:—

1. A shipping and storing package for goods including in combination, a hermetically sealed and waterproof metallic casing 25 for containing the goods, a relatively light metallic protective casing for receiving the hermetically sealed casing, reinforcing strips secured to the inner surface of the protective casing, and a reinforced cover 30 for said protective casing.

2. A shipping and storing package for goods as claimed in claim 1, wherein the reinforcing strips are formed of wood and wherein the cover is flanged and telescoped over the casing, and means for securing the 35 flanged cover to the casing, said securing means being anchored in the reinforcing strips.

3. In a shipping and storing package for goods, a hermetically sealed and waterproof 40 metallic casing for containing the goods, metallic buffer strips arranged within the casing prior to the sealing thereof for protecting the ends of the casing against the action of the relatively heavy plates adapted to be shipped in the casing, and an outer protective casing for the hermetically sealed casing.

4. A shipping and storing package for goods as claimed in claim 3, wherein the 50 buffer strips consist of pieces of metal having the respective ends bent angularly and reversely folded so as to lie between the corners of the plates being shaped so as to absorb shocks, substantially as and for the 55 purposes set forth.

In testimony whereof I have signed my name to this specification.

DAVID GEORGE.
